COIN SELECTOR

Benjamin W. Fry and John Gottfried, St. Louis,
Mo., assignors to National Slug Rejectors, Inc.,
St. Louis, Mo., a corporation of Missouri

Application January 8, 1938, Serial No. 183,939

2 Claims. (Cl. 194—102)

This invention relates to coin selectors designed to eliminate coins or slugs which are defective in any one of a number of ways and to direct accepted coins into position to control the functioning of dispensing mechanism. More particularly, the invention contemplates improved means for bringing about the rejection of coins or slugs which are undersize or have excessively rough surfaces or apertures.

10 The invention is a coin selector comprising a single strong permanent magnet disposed with its two poles on opposite sides of a coin passage of relatively small inclination. This magnet functions not only to retain in the passage coins or slugs which are magnetic, but also to so control the movement of non-magnetic coins and slugs as to effect the separation of those of improper electrical conductivity from those which are acceptable. Associated with the magnet and the inclined coin passage are devices for retarding or retaining apertured or rough surfaced slugs and devices by which the passage may be opened for the ejection of slugs retained therein and such slugs positively ejected.

25 The present invention provides novel devices for retaining in the coin passage apertured, rough surfaced or undersize disks and means for the subsequent ejecting of the disks thus retained. The invention likewise provides novel means associated with the dispensing mechanism for bringing about such ejection.

In the drawing

Fig. 1 is a side elevation of a coin selector and dispensing mechanism control including one embodiment of the present invention. For convenience the side of the device shown in Fig. 1 will be referred to as the "front" and the opposite side as the "rear," although it will be understood that in use the part of the device which faces the operator is the "edge" facing toward the left in Fig. 1.

Fig. 2 is an elevation of the opposite or rear side.

Fig. 3 is a sectional side elevation substantially on the line 3—3 of Fig. 4.

Fig. 4 is a sectional elevation substantially on the line 4—4 of Fig. 2.

The device is built upon a vertically disposed main plate 10 which plate forms the leftward or rear side of the entrance passage, the passage including the selecting mechanism to be described, and the passage for accepted coins. To ears 11 projecting from the main plate 10 is pivoted a frame identified generally by the numeral 12. Said frame comprises a top bar 13 and a

bottom bar 14, both of which are inclined downwardly and rearwardly. To the bottom bar 14 is secured a ledge or coin support 15 forming the bottom of a coin passage or race-way. The opposite face of ledge 15 rests throughout at least a portion of its length against the inner or front face of plate 10. In passing through the selector, disks are supported edgewise upon the upper surface of the ledge 15. Bars 13 and 14 are joined by a rear frame bar 16 and a front frame bar 17, the bar 17 being widened and offset to provide a widened entrance slot and a lateral support for disks inserted in the selector. To the upper part of plate 17 is secured a light leaf spring 18 carrying at its free end a pin 19 which normally rests against the front face of the main plate 10 but is deflected by a disk dropping through the passage between the main plate 10 and the lower part of bar 17 to rest against the front face of said disk and not only to retain or retard disks which are apertured or rough surfaced but likewise to press all disks toward the face of the main plate 10 and thereby facilitate the functioning of the selecting device to be described. A shield 20 may be secured to the offset portion of the front plate 17 to extend over and protect the light spring 18 from injury without interfering with its function.

It will be understood that when the frame 12 is rotated about its pivots to remove the ledge 15 from contact with the main plate 10 that a coin or disk inserted in the device will fall past this ledge instead of upon it. Suitable devices are provided for urging the frame toward the main plate 10 to establish the coin passage. For this purpose the rearward pivot 21 of said frame may be elongated and support a coil spring 22, one end of which bears against the front face of the main plate 10 while the opposite end is received by a stud 23 projecting from a boss on the bar 16. To effect the opening of the coin passage by moving the frame 12 away from the plate 10 the stud 23 may be provided with a roller 24 adapted for engagement by the downwardly and rearwardly inclined margin of a lip 25 projecting forward through an aperture in the main plate 10 from a lever 26 pivoted at 27 on the rear (Fig. 2) face of said main plate. The lip 25 of lever 26 likewise overlies and depresses a scavenger lever 28 pivoted to the main plate at 29 and urged upwardly by a spring 30.

A magnet 31 is held in front of and spaced from plate 10, in such a position that its pole faces form parts of the side of the coin passage above ledge 15, by suitable means, such as a frame comprising a plate 32 secured to and in contact with plate 33.

10, a bar 33 extending between the poles of the magnet, a front plate 34 forming a part of the side of the coin passage, and a bottom bar 35 joining the lower ends of bar 33 and plate 34. 5
 5 Opposite the magnet 31 is a second similar magnet 36 held on the rear side of plate 10 with its poles projecting through apertures to be substantially flush with the front face of said plate.
 The present invention includes novel means co-operating with the pin 19 for retaining undersize disks in the coin passage. This means comprises a recess in the coin passage wall opposite pin 19, into which undersize disks are moved, but which full size coins "bridge" and do not enter. 10
 15 The plate 10 comprises an aperture 40 having a dimension in the direction of the coin passage past the magnet which is somewhat greater than the diameter of the largest disk which can be inserted in the device. The margin of this aperture toward the magnet presents a shoulder 41 adapted to engage the margin of an undersize disk and thereby retain such disk. Adjacent the lower margin 42 of aperture 40 the front face of plate 10 is cut back to form an inclined face 43. To 20
 25 the rear side of plate 10 is secured a member 44 which partly covers the aperture 40. Near the upper margin of member 44 is formed a ledge 45 which extends through the aperture 40, its front face being substantially flush with the front 30
 35 face of plate 10. There is thus provided a disk retaining pocket defined by the lower margin 46 of the ledge 45, the shoulder 41, the inclined face 43, and the upper margin of ledge 45. The lower margin 46 of ledge 45 is spaced from the upper margin of coin supporting ledge 15 by a distance slightly less than the diameter of a correctly sized coin, and when a coin of proper size is dropped through the entrance passage between plate 10 and plate 17 upon ledge 15 its upper portion 40
 45 is in lateral engagement with the front face of ledge 45. If such a coin is of proper surface characteristics and is therefore not retarded by the pin 19 it rolls down the ledge 15 into position for further testing by the magnet. However, a 50
 55 disk which is slightly undersize will upon dropping through the entrance passage on to ledge 15 clear and drop beneath the ledge 45, being pressed laterally to a position beneath said ledge by the spring urged pin 19. When a disk in this position begins to roll down the supporting ledge 15 it 60
 65 immediately engages the margin 41 of aperture 40 and is thus retained in the passage. A simple and remarkably effective means of detecting and retaining undersize disks is thus provided.
 70
 55 Undersize disks retained in the selector in the manner above described as well as rough or aper-tured disks retained by the pin 19 or magnetic slugs retained by the magnet may be removed therefrom by the opening of the passage by oscil-lating the frame 12 in conjunction with the posi-tively acting scavenger 28. When so removed they drop along the front face of plate 10 until they are laterally deflected by the downwardly and forwardly inclined ledge 45 into the passage 65
 75 for rejected coins. The frame and scavenger may be actuated upon the insertion of a second coin or disk or by separate manipulation in the manner described in prior applications and patents of the present inventors. Preferably, however, means are provided that not only signal an attempt to operate the dispensing mechanism by a coin which is not acceptable, but also cause the ejection and return of said coin. The device for this purpose which has been selected for illustration may be 70
 75 described as follows:

The dispensing mechanism is operated by a lon-gitudinally sliding actuator bar 50 which may be mounted in a trackway 51 formed integral with or secured to a plate 49 which forms the front side of the passage for accepted coins and the rear side of the passage for rejected coins. Suitable means such as a spring 52 tensioned between an ear 53 on the bar 50 and a lug 54 on the plate 10 urge the actuator bar 50 forward. Accepted coins drop into a pocket associated with bar 50 which pocket may be conveniently formed by fix-ing to said actuator bar a yoke 55. Adjacent the rear margin of said pocket is a latch 56 which extends transversely from a lever 57 pivoted to the member 49 at 58 and urged counter-clockwise 15 (Fig. 1) by suitable means such as a spring 59. The latch 56 co-operates with a cut-out 60 in the actuator bar 50. If there is no coin in the pocket formed by yoke 55 and an attempt is made to move the actuator bar rearwardly to operate the dispensing mechanism, the margin or shoulder 61 of cut-out 60 will be engaged by latch 56 after the actuator bar has moved a limited distance but before the dispensing mechanism has been oper-20 ated, and further movement of the actuator bar is thus stopped. If there is a coin in the pocket the margin of the coin engages the latch 56 and cams it upwardly to clear shoulder 61 of the ac-tuator bar and permit its complete movement. 25
 Means are provided for operating the lever 26 to open the coin passage and operate the scav-30 enger to eject and return a retained slug by the initial movement of the actuator bar 50; that is, the movement the actuator bar may be given in the absence of a coin in its pocket. Such 35 means may be variously constructed. For the purpose of illustration there is shown in the draw-ing a stud 62 provided with a roller 63 projecting laterally from the actuator bar 50 in position to engage and actuate a lever 64 pivoted at 65 to 40 the main plate 10. The opposite end of lever 64 is connected by a link 66 with an ear 67 extending laterally from the lever 26. Thus the first effect of moving the actuator bar 50 inward is to rock the lever 64 and the lever 26, thereby eject-45 ing and returning any slugs which are lodged in the coin passage. If there is a coin in the pocket formed by yoke 55, the latch 56 is cammed out of the path of movement of shoulder 61 and the movement of the actuator bar 50 may be com-50 pleted. With the actuator bar 50 is associated a suitable manipulative device (not shown), and there may be provided a suitable full-stroke de-vice comprising a pawl 68 pivoted upon the actu-55 ator bar and a co-operating ratchet 69 associated with the member 49.

The operation of the device may be summa-rized as follows:

When a coin of proper size and otherwise ac-ceptable is inserted, such coin drops between 60 the main plate 10 and the plate 17 on to ledge 15. Its upper portion is laterally engaged by the front face of ledge 45, and the coin is thus properly positioned to roll past the magnets 31 and 36 and into the passage for accepted coins, 65 which passage terminates in the coin pocket in actuator bar 50. Actuator bar 50 may then be actuated through the full-stroke necessary to operate the dispensing mechanism, the margin of the coin acting as a cam to displace the actu-70 ator bar latch 56. In completing the movement of the actuator bar 50 the coin which initially rests therein upon a ledge 68 associated with member 49 drops through an aperture in said ledge into a coin receptacle. 75

When an undersize coin is inserted in dropping upon the ledge 15 it passes below the ledge 45 and is pressed beneath said ledge by pin 19. When it begins to move forward it engages the face 41 and is thus stopped and retained. The actuator bar 50 may now be moved only through the distance separating shoulder 61 from latch 56, but in this movement roller 63 on stud 62 has engaged and operated lever 64 which in turn 10 operates lever 26 to open the coin passage, actuate scavenger 28, and thus dislodge and return the unacceptable undersize disk. Disks or slugs which by reason of any other defect are retained in the coin passage are similarly dislodged and 15 returned.

The embodiment of the invention illustrated and described is merely a typical and representative one, the invention being susceptible to variations and modifications all falling within the 20 scope of the appended claims.

What is claimed is:

1. A coin selector comprising means forming a sloping passage down which acceptable coins roll, on their edges, disposed in a vertical plane, 25 said means being laterally recessed on one face thereof and provided with a shoulder flush with the recessed face at an elevation above the bottom of the passage greater than the diameter of rejectable coins and less than the diameter of acceptable coins, and means associated with the 30 passage-forming means urging all coins laterally in the direction of said recess, whereby coins of rejectable diameter are forced by said last-named means to tilt into said recess, but coins of 35 acceptable diameter roll past said recess in ver-

tical position with their upper extremities resting against said shoulder, said recess terminating along the length of said passage as an upstanding shoulder against which said tilted rejectable coins lodge, and means for discharging 5 such lodged coins.

2. A coin selector comprising means forming a sloping passage down which acceptable coins roll, on their edges, disposed in a vertical plane, 10 said means being laterally recessed on one face thereof and provided with a shoulder flush with the recessed face at an elevation above the bottom of the passage greater than the diameter of rejectable coins and less than the diameter of acceptable coins, and means associated with the 15 passage-forming means urging all coins laterally in the direction of said recess, whereby coins of rejectable diameter are forced by said last-named means to tilt into said recess, but coins of acceptable diameter roll past said recess in vertical position with their upper extremities resting against said shoulder, said recess terminating along the length of said passage as an upstanding shoulder against which said tilted rejectable 20 coins lodge, said urging means likewise being 25 adapted to frictionally engage the surface of coins of proper diameter but improper surface formation to deter such coins from further rolling movement in said passage, and means for discharging lodged coins of rejectable diameter and 30 coins of improper surface formation from said passage.
